AIR COMPRESSOR

Elmer F. Baumgart and George E. Willard,
Danville, Ill.

Application November 5, 1948, Serial No. 58,442

1 Claim. (Cl. 230—38)

1

Our invention relates to air compressors and more particularly to a demountable unit which can be readily attached to the power take-off shaft of a variety of tractors, or generally any source of power.

Compressors of the type contemplated by this invention are customarily used by farmers as a source of compressed air for the tractor tires whose pressure is desirably varied for maximum traction in accordance with the nature and condition of soil over which the tractor operates, and also for spraying, and may also be used by contractors of various kinds, the military service, and industrial concerns. Ordinarily, such compressors are held against rotation thereof due to the rotative thrust of the power take-off shaft by chains or cables, but these holding features are objectionable in that they are awkward and capable of inflicting injury on the operator if they become unattached while the pump is working.

Cardinal requirements of such compressors are that they be rugged in construction while embodying simplicity of design which is reflected in low manufacturing costs and, further, that they may be easily disassembled and assembled for purpose of repair and replacement.

It is therefore one object of our invention to devise a compressor that may be rigidly clamped against rotation to a demountable part that is securely fastened to the rear axle housing of a tractor, or generally any device having a power take-off shaft, thus eliminating all necessity for attaching chains and cables.

A further object is to provide a compressor that is constructed and arranged to avoid any necessity for a bearing for the hollow crankshaft which is merely slipped over the end of the power take-off shaft.

A further object is to devise an adapter on which the compressor is supported and which is securely fastened to the rear axle housing in the location normally occupied by the safety cap that encloses the exposed end of the power take-off shaft.

A further object is to provide an air compressor of the character indicated which can be fabricated from simply shaped parts and quickly assembled by unskilled labor.

These and further objects of my invention will be set forth in the following specification, reference being had to the accompanying drawings, and the novel means by which said objects are effectuated will be definitely pointed out in the claim.

2

In the drawings:

Figs. 1 and 2 are side and end views, the latter partly in section, respectively, of our improved compressor in working relation to the end of a power take-off shaft.

Fig. 3 is an enlarged, sectional elevation of the upper end of the compressor, the crank disk being displaced from the position shown in Fig. 2.

Fig. 4 is a section along the line 4—4 in Fig. 3.

Fig. 5 is a fragmentary, plan view of the hollow crankshaft looking in the direction of the arrow 5 in Fig. 3.

Referring to Fig. 3 of the drawings, the numeral 10 designates the rear axle housing of a typical tractor having an opening 11 through which extends the splined end of a power take-off shaft 12 that is appropriately connected to the tractor engine. Mounted in the opening 11 and secured to the housing 10 is a tube 13 which is spaced from and is coaxial with the shaft 12 and may carry a bearing 14 for the shaft. One end of the tube 13 extends outwardly of the housing and is internally threaded at 15 to normally receive a cap (not shown) which encloses the exposed end of the shaft 12 as a safety factor. So far as described, the construction is standard on many tractors and advantage thereof is taken in devising our improved rigid mounting for the compressor. It will be understood, however, that the compressor is not restricted to use with a tractor, since it is capable of being demountably connected to any device having a power take-off shaft, or generally any device having a driving shaft, one end of which is exposed.

35 One end of a sleeve 16 is threaded in the tube end 15 so that the former is concentric with the shaft 12. The upper end of a frame 17 is bored at 18 to slip over the exposed end of the sleeve 16 and includes a pair of facing, semi-circular jaws 19—19 formed by slitting the upper extremity of the frame at 20, as shown in Fig. 2. Each of these jaws is provided with a boss 21 and threaded through both bosses is a screw 22. By tightening the screw 22, it will be obvious that the frame 17 will be anchored to the sleeve 16.

The opposite or lower end of the frame 17 includes a laterally extending platform 23 having a bearing boss 24 through which is slidable a piston rod 25. The upper end of the piston rod 25 is pivotally connected to one end of a connecting rod 26 whose opposite end is journaled on a crankpin 27 that is welded or otherwise secured to the outer face of a crank disk 28 at an appropriate radial distance from the center thereof. 55 As indicated in Fig. 3, the opposite side of the

disk 28 has welded or otherwise secured thereto a hollow crankshaft 29 which is coaxial with the disk and is arranged to fit over the take-off shaft 12. Driving connection between the crankshaft 29 and the shaft 12, in the present instance, is effected by inwardly offsetting a portion of the former to provide a tooth 30 which fits one of the grooves in the shaft 12. The disk rotates within a counterbore 31 provided in the adjacent face of the frame 17 and, when the compressor is operating, axial movement of the disk away from the shaft 12 is restrained by a pair of semi-circular strips 32-32 which are fastened to the frame 17 with their opposed ends spaced sufficiently to permit the clamping action of the jaws 19-19 to which reference has been made.

The opposite or lower end of the piston rod is connected to a piston 33 comprising an inverted cup 34 whose base is clamped between disks 35 and 36 that are fastened to the rod 25. In accordance with well known practice in pistons of this type, the cup 34 may be made of leather, rubber or any leak proof material having sufficient flexibility to insure that the annular wall of the cup will closely hug the wall of a cylinder shell 37 during compression strokes and will withdraw slightly during suction strokes to permit air to flow into the compression chamber.

The upper end of the shell 37 is recessed in the under side of the platform 23 and the lower end in a header 38, and tie rods 39 hold these parts in the positions shown. The header 38 includes an exhaust port 40 which is closed during suction strokes of the piston 33 by a spring actuated valve 41 and when the latter is opened during the compression stroke, the compressed air is discharged through the port 40 and a hose 42 to the part being serviced. During suction strokes of the piston 33, air is admitted to the shell 37 through screened passages 43 provided in the platform 23.

To mount the compressor in operative relation to the take-off shaft 12, the safety cap (not shown) that encloses the exposed end of the shaft is removed and replaced by the sleeve 16 which is screwed tightly in the tube 13 and functions as an adapter support to receive the upper end of the frame 17 while the hollow crankshaft 29 is slipped over the end of the shaft 12 in driving relation thereto. The screw 22 is then tightened, thus firmly anchoring the compressor against the rotative thrust of the shaft, while any tendency of the latter to axially throw the crankshaft 29 is prevented by the restraining action of the strips 32 which are carried by the frame 17.

The adapter sleeve 16 is an important feature of the invention since it may be quickly and easily secured to an existing part of many tractors to provide a support for the compressor which is clamped thereon, free of any necessity for attaching chains or cables, or an arm carried by the compressor which engages a part of the tractor to prevent rotation. Further, the sleeve insures the positioning of the bored end of the frame in coaxial relation to the shaft 12 and when the crankshaft 29 is in driving engagement with the shaft 12, the crank disk 28 is similarly related to and is supported by the latter shaft so that it may freely rotate within the space included between the strips 32, and the adjacent portions of the frame 17 and the sleeve 16. Generally speaking, the stationary parts of the compressor are carried by the sleeve 16, while the working parts are supported by the shaft 12. It is accordingly unnecessary to provide bearings for either the crankshaft 29 or the disk 28 with resultant manufacturing economies. The piston bearing 24 is adequate to prevent the transmission of any side thrusts to the piston 33 by the connecting rod 26.

We claim:

An air compressor comprising an adapter sleeve arranged for detachable mounting on a device in coaxial relation to a splined driving shaft thereof, a frame detachably secured to the sleeve, a pump cylinder having a piston carried by the frame, a hollow crankshaft for telescopically receiving the driving shaft within the sleeve and being inwardly toothed for driven engagement with the driving shaft, the crankshaft being freely insertable within and spaced from the sleeve, and driving connections between the crankshaft and piston including a piston rod slidable in the frame.
